DESIGN FOR A WALL VASE OR ARTICLE OF SIMILAR NATURE

Clifford Potts, Zanesville, Ohio, assignor to Louis
A. Butler and Arvilla K. Butler, doing business as Ohio Porcelain Company, Zanesville, Ohio

Application December 18, 1947, Serial No. 143,212

Term of patent 7 years

(Cl. D29—28)

To all whom it may concern:

Be it known that I, Clifford Potts, a citizen of the United States of America and a resident of Zanesville, in the county of Muskingum and State of Ohio, have invented a new, original, and ornamental Design for a Wall Vase or Article of Similar Nature, of which the following is the specification, reference being had to the accompanying drawing, forming a part hereof:

I claim:

The ornamental design for a wall vase or article of similar nature, substantially as shown.

CLIFFORD POTTS.
